US0D1095942S

(12) **United States Design Patent** (10) **Patent No.:** **US D1,095,942 S**
(45) **Date of Patent:** **** Sep. 30, 2025**

(54) **LIGHT DIFFUSER FOR LIGHTING DEVICES**

(71) Applicant: **Ledil Oy**, Salo (FI)

(72) Inventor: **Matti Vuola**, Salo (FI)

(73) Assignee: **LEDIL OY**, Salo (FI)

(**) Term: **15 Years**

(21) Appl. No.: **29/922,792**

(22) Filed: **Dec. 26, 2023**

(30) **Foreign Application Priority Data**

Jun. 29, 2023 (EM) 015026318-0002

(51) **LOC (15) Cl.** **26-05**

(52) **U.S. Cl.**

USPC **D26/118**; D26/120

(57) **CLAIM**

The ornamental design for a light diffuser for lighting devices as shown and described.

DESCRIPTION

FIG. 1 is a top perspective view;

FIG. 2 is a bottom perspective view;

FIG. 3 is a top view;

FIG. 4 is a bottom view;

FIG. 5 is a front view; and,

FIG. 6 is a right view.

1 Claim, 6 Drawing Sheets

FIG. 1

FIG. 2

FIG. 3

FIG. 4

FIG. 5

FIG. 6
